UNITED STATES PATENT OFFICE.

JOHN THOMSON, OF BROOKLYN, NEW YORK.

ENGINE PISTON.

Application filed August 29, 1922. Serial No. 585,022.

To all whom it may concern:

Be it known that I, JOHN THOMSON, a citizen of the United States, and a resident of the borough of Brooklyn, city and State of New York, have invented an Engine Piston, of which the following is a specification.

This invention relates to reciprocating engine-pistons, and is comprised in improvements whose dominant objects are to effect an enduring, tight seal against the actuating pressure, as of gas or steam; to largely, or even wholly, avoid the use of oil as a lubricant; and to substantially enhance the efficiency of engine-pistons and their cylinders. Various correlated improvements and advantages will hereinafter be pointed out.

The essence hereof may be thus briefly summated: such a utilization of monolithic graphite, and of solidified carbon-graphite, in the form of sleeves or tubes, combined with metal, whereby the graphite, when cool, will traverse the engine-cylinder comparatively free; but, when heated by the gas or steam, it will be expanded into a closer and more enduring physical contact with the cylinder-wall than would be possible in the case of a metal-to-metal contact.

As above employed, the term "monolithic graphite" relates to amorphous carbon which has been graphitized in an electric furnace, as by the process of Acheson. As thus produced, it is nearly perfectly pure in that all of the primary binding material has been volatilized; as a lubricant, it stands second only to oil; and, although this fact is not generally known, it is considerably compressible and highly resilient. The term "carbon-graphite" includes artificial or natural graphite, or amorphous carbon, in the form of powder, dust or flakes, with which is mixed some modicum of binding material, such as the kaolins, sodium silicate, bitumen or the like; and, when plastic, is molded or extruded to the desired form and thenafter baked in kilns. The lubricating quality of carbon-graphite does not equal that of the electrically graphitized product; but, in various cases, it has compensating features, such as being denser, more resistant to shock and is readily inexpensively moldable in metal dies with a close approximation to accuracy. Therefore, when the term, graphite, is hereinafter used it is to

be understood as referring, in general terms, to various monolithic and solidified forms and mixtures.

Although an academic statement, it may be here mentioned that the functioning of graphite as a lubricant, in the forms described, proceeds about as follows: Molecular-like-particles are firstly ripped off, or torn, from the contacting surface and are then transferred into the microscopic pores and "hollows" of the co-ordinating metal; whereby, once a balance is established, the sliding surfaces in fact become graphite-on-graphite, whose co-efficient of friction is probably the least of any non-fluid substance.

In the drawings, which constitute a part of this specification,

Figure 1 is an elevation of the piston depicting an effective embodiment of the invention;

Figure 2 is an end view, developed from Figure 1, looking into the interior of the piston;

Figure 3 is a vertical center section of the piston and its connecting rod pin-bracket, as on the line A of Figure 2;

Figure 4 is a transverse section, as on the lines B, or B¹, of Figure 3;

Figure 5 is a detached, end elevation of the aforesaid pin-bracket;

Figure 6 is a broken vertical center section showing the bracket and pin in place and also depicting a detail modification in construction;

Figure 7 is a half-elevation and a half-vertical section of a graphite sleeve in its primary form;

Figure 8 is a transverse section, as along the lines C, or C¹, of Figure 7;

Figure 9 is a half vertical center section and a half elevation of a piston in the rough, prior to being machined to its finished dimensions, denoted by the broken lines D, D¹;

Figure 10 is a half end view and a half transverse section, the latter taken as along the lines E or E¹ of Figure 9; and

Figure 11 denotes a detail modification in the construction over that of Figures 7 and 8.

The drawings are approximately full scale reproductions of designs reduced to practice, as applied to a "Buick" automobile.

It should be borne in mind that to effec-

tively withstand the explosive shocks, high speed of action and the rapid and extreme changes in temperature imparted to, say, a gas engine piston, the graphite must be applied with the very utmost rigidity possible to attain; and, as the tensile strength of graphite, or of carbon-graphite, is low whilst its crushing resistance is relatively high, the one best way of attaining the desired end is to utilize the graphite in such manner that it shall be largely held and gripped under compression; which is so applied as not to also produce other than nominal tensile stresses.

The employment of a single graphite sleeve is deemed a highly effective mode of realizing the benefits of this invention, in that the greatest area of bearing surface is thereby afforded and but one such member has to be dealt with. Thus, the sleeve 25, in its primary form, as see Figure 7, does not require, at this stage of the manoeuvre, to be finished with accuracy. If formed by machining it from a solid round rod, or if extruded, or if molded, it is then provided with a plurality of transverse slots, as 26, preferably cut by a circular saw, indicated by the dotted outline 27, Figure 8, which is sunk into and through the sleeve from its exterior surface; and whilst the inner length of each of the slots, as notated, may be 1 inch, the outer length may be $1\frac{1}{8}$ inch. This slotted sleeve is then placed in an ordinary green sand mold, as in the case of a baked sand core, which co-ordinates with a suitable pattern of the desired piston, when molten metal is run into the mold-cavity. In this wise, the cylindrical metal portion M, and the enclosing head N, are formed; and the aforesaid slots are filled with molten metal, as 28, which, when solidified, subjects the graphite to the utmost degree of compression that the shrinkage of the metal from the molten to the solid state is capable of imparting, vertically between the sides of the metal, as J in Figure 9, and also radially, towards the center, as P in Figure 10, this secondary action being due to the wedge-shaped interlock of the metal in the slots of the graphite.

The dotted lines, D, D¹, Figures 9 and 10 denote the final finished contour in the casting, or as is shown in the completed form of Figures 1, 2, 3 and 4.

As will be perceived by inspection of the aforesaid figures, the entire surface of the piston, outside and inside, is machine finished; the primary advantage of which is that the cylindrical metal portion may be much thinner and lighter than would otherwise be possible; but, as a correlative thereto, the hubs in which the connecting rod pin is mounted must be separately applied. This is accomplished by forming the hubs 30, 31, upon extensions, 32, 33, rising from

a circular base, 34. The outer hub-surfaces, as 35, Figure 5, are finished to the circular contour of the inner wall of the piston, and a threaded bore, 37, in the base is adapted to a threaded hub, 38, on the piston-head. In this wise, the base of the pin-bracket can be forced into very intimate contact with the piston-head; which can be made thinner than ordinarily, as the circular base of the bracket serves as a reinforcement. When the bracket is thus secured, the bearing for the connecting rod pin is drilled through the piston and the bracket-bosses and when the pin itself, as 39, is inserted, the impelling thrust is largely imparted thereto directly from the piston-head and also, but to a considerably lesser extent, from the piston-wall.

In some cases, the connecting rod rocks on the pin, in other cases the pin rocks in the piston. When the latter is practiced the bearing quality of hubs may not be, and usually is not, of first grade for the onerous duty performed. But by means of this separate pin-bracket it is then feasible to form it of the most enduring material possible to utilize.

In a gas engine, the temperature imparted to and retained by the piston is substantially higher than that of the containing cylinder; and the enclosed head of the piston will be maintained at a higher temperature than its open or skirt-portion. Consequently, and dependent upon the co-efficient of expansion and contraction of the material used, the diameter, or diameters, of the piston will be less, when it is cold, by some thousandths of an inch, than the bore of the cylinder. Therefore, the prevailing practice is to so adapt the diameters that the piston, when heated, shall be closely contiguous to but not in intense physical contact with the cylinder-wall; for, whatever may be the combination of metals, if the piston is so expanded as not to afford oil-space, it is bound to cut, score or "freeze". Per contra, when the material of the piston which is expanded to a state of even absolute physical contact with the cylinder-wall is graphite, or carbon-graphite, cutting and scoring do not ensue. In fact, if the impingement is tighter than it ought to be, the graphite acts to clear itself. A most important contingent advantage is here derived, namely: As the graphite is self-lubricating, and as it can be fitted more closely than in the case of metal, oil is kept out of the explosion chamber and the formation of hydro-carbon therein is diminished to a minimum, or even wholly avoided.

When the graphite is finished to the exact diameter required, the diameters of the obtruding metal segments are reduced, by forming circular recesses, as 40, Figures 1, 3 and 4, whereby to prevent any metallic contact with the cylinder; moreover, this oper-

ation also provides excellent "baffle grooves", which serve to arrest a free vertical leakage of gas, vapor or oil.

- 5 The utmost attainment of operative efficiency is aided by applying an ordinary split metal packing ring, as 41, preferably disposed in a recess near the head of the piston, whose particular function is to temporarily hold the initial compression when the piston 10 is cold. As this ring traverses the highly polished and graphited surface of the cylinder, the condition of the operation is much more favorable for long endurance than in existing practice. If desired, the split ring 15 may be mounted in the graphite, as is shown in Figure 6.
- As previously mentioned, monolithic graphite is compressible and resilient. These functions are aids to the success of 20 this system; for, if the graphite is driven by heat-expansion into an excessive intimacy of contact with the cylinder, it will compress, but, due to its resiliency, a permanent set does not ensue.
- 25 Various detail modifications may be made according to the wishes of users or designers.

For example, instead of forming the slots in the sleeve, they may be substituted by numerous drilled holes, preferably tapering outwardly, as 42, Figure 11, and the pin 30 bracket may be riveted, or electrically welded, or both, to the piston instead of being attached as shown.

What I claim is:

1. An engine piston formed of a metallic headed cylinder and an exterior sleeve of solidified graphitic carbon, said sleeve being provided with a plurality of wedge-like slots primarily filled with molten metal; whereby, when chilled, the graphitic sleeve is compressed vertically and radially. 35

2. An engine piston formed of an exterior tube of solidified graphitic carbon and an inner metallic cylinder in which portions of the metal extend through the graphitic tube, 40 the perimeters of said portions being reduced to diameters lesser than that of the co-ordinating surface of the engine-cylinder. 45

This specification signed on this the 28th day of August, A. D., 1922.

JOHN THOMSON.
